UNITED STATES PATENT OFFICE.

PATRICK J. WALSH, OF MORRIS, ILLINOIS.

RADIATOR ATTACHMENT.

Application filed October 3, 1925. Serial No. 60,364.

The present invention relates to a radiator attachment for the purpose of furnishing humid and clean air from a radiator. This is companion application to the application filed by me under date of September 9, 1925, and assigned Serial No. 55,278, and another application Serial No. 60,365 which is being filed on even date with this application.

The prime object of the invention is the provision of an attachment of this nature which consists of a pan adapted to hold a supply of water over the radiator for evaporation and to cover the pan with a shield, a portion of which consists of suitable cleaning material such as cotton batting for the air to pass thru encased between two foraminous sheets.

A specific object of this invention is the provision of an improved air cleaning attachment for radiators which is of simple construction, and one which is thoroughly reliable and efficient in use.

A still further object of the invention is to provide an attachment of this nature which may be easily assembled and disassembled, one which possesses superior compactness and convenience, may be manufactured at a comparatively low cost, is strong and durable, and is otherwise well adapted to the purpose for which it is designed.

With the above and numerous other objects in view as will appear as the description proceeds, the invention resides in certain novel features of construction and in the combination and arrangement of parts as will be hereinafter more fully described and claimed.

In the drawing—

Figure 1 is a front elevation of the attachment showing the same in place on a radiator,

Figure 2 is a vertical section therethrough, and

Figure 3 is a section taken substantially on the line 3—3 of Figure 2 but showing the pan partly in elevation.

Referring to the drawing in detail, it will be seen that the attachment consists generally of three parts, a pan A, supporting brackets B, and shield C. The supporting brackets have been disclosed and described in detail in my application, Serial No. 55,278 above referred to, and no more than a general reference in this application seems necessary.

The pan A is disclosed and described in detail in my companion application Serial

No. 60,365, but will be described herein sufficiently in detail to bring out the cooperation thereof with the other elements of the combination.

Referring now in detail to the pan A, it will be seen that the same is supported on the brackets B by ends D. Each end D includes a side 5, a top 6, a side 7 longer than the side 5, and merging into an inclined upright 8 which in turn merges into a bottom 9 having the depending rectangularly disposed flange terminals 10. The sides 7 are disposed outermost. These ends D are adapted to rest on the brackets B as is apparent. The pan proper or the body thereof includes a bottom 11, end walls 12 which are soldered, welded, or otherwise permanently attached to the sides 5 of the ends D, a rear wall 13 of the same height as the end walls 12, and a front wall 14 less in height than the walls 12 and provided on its upper edge with an inwardly disposed right angularly extending flange 15. The pan proper is adapted to receive water which will be evaporated by the heat rising from the radiator.

Referring now in detail to the shield C, it will be seen that the same is formed in two parts, E and F. The part E is formed from a sheet of metal bent to provide the top portion 17, the slanting rear wall 18, and the bottom 19 extending parallel with the top 17. The top 17 is adapted to rest on the top 6 of the ends D, while the bottom 19 is adapted to extend under the lower edges of the brackets B behind the radiator. Part F includes suitable cotton batting 20 or the like disposed between a relatively fine mesh 21 of foraminous material and a comparatively coarse mesh 22 of foraminous material. The foraminous sheets 21 and 22 are soldered one to the upper surface and the other to the bottom surface of the top 17. The sides and one end of the sheet 21 are folded over upon the sheet 22 as is indicated specifically at 23 and 24 respectively and soldered or otherwise secured to the sheet 22. If desired, however, these folded portions 23 and 24 need not be secured to the sheet 22 in order that they may be unfolded for the removal of the cotton batting or other air cleaning material.

When this attachment is mounted on the radiator as is shown in Figs. 1 and 2, it will be seen that heated air from the radiator will rise under the pan A for causing the evaporation of the water therein, there-

by humidifying said heated air and causing the same to pass through the cotton batting so as to separate any dust therefrom, thereby causing the circulation in the room of clean humid air which, of course, is most desirable. The assemblage of the necessary elements for producing this attachment possesses superior compactness and convenience as is apparent, and because of the simplicity 10 of the parts, the same may be placed on the market at a comparatively low cost and yet will prove strong, durable, as well as thoroughly efficient and reliable in use.

It is thought that the construction, utility, 15 operation, and advantages of this invention will now be clearly understood without a more detailed description thereof. The present embodiment of the invention has been disclosed merely by way of example 20 since in actual practice it attains the features of advantage enumerated as desirable.

in the statement of the invention and the above description. It is apparent that numerous changes in the details of construction, in the materials, in the sizes, and the 25 above combination and arrangement of parts may be resorted to without departing from the spirit or scope of the invention as hereinafter claimed or sacrificing any of its advantages.

Having thus described my invention, what I claim as new is:—

An air humidifying attachment including, in combination, a pair of supporting brackets, a pan resting on the supporting brackets for holding a quantity of water and a shield disposed over the pan and extended under the brackets for holding the pan on the brackets against accidental misplacement.

In testimony whereof I affix my signature.

PATRICK J. WALSH
